THERMOSTATIC FLUE REGULATOR

Filed Feb. 16, 1929

Inventor:

Arthur C. McWilliams

By Albert Schubh.
Attorney.

UNITED STATES PATENT OFFICE

ARTHUR C. McWILLIAMS, OF CHICAGO, ILLINOIS

THERMOSTATIC FLUE REGULATOR

Application filed February 16, 1929. Serial No. 340,567.

My invention relates to dampers for a flue pipe or the like; and in its general objects aims to provide a damper which can be manually adjusted in position to afford a desired effective minimum passage through the pipe, and which will automatically increase this minimum passage when the pipe cools and annul the increase when the temperature rises.

10 In operating both coal-burning and oil-burning heaters, the efficiency of such heaters depends to a considerable extent on the effective size of the passage for the combustion gases. The maintaining of a high efficiency 15 involves a much more frequent adjustment than can be expected manually from any attendant, and also requires adjustments more accurately proportioned to the temperature of the gases in the flue than can be made by 20 an ordinary attendant.

Moreover, with any given heater, the maximum effective passage through the flue may also need to be adjusted according to the nature of the fuel and according to the barometer. If these adjustments are also left to 25 the average attendant, an error in attending to them may lead to so-called "puff-backs" with oil burners, and to an extinguishing of the fire in a coal-burning heater, in addition 30 to increasing the fuel consumption.

My present invention aims to overcome all of these objections by providing a main damper which can be manually adjusted and latched in any one of a number of definitely 35 determined and positively indicated positions, in each of which positions the main damper will afford an effective flue passage of a definitely known cross-section ranging from an approximately full flue opening to a 40 partial opening of definite proportion to this full flue opening; and also aims to provide a thermostatically operated secondary damper (or "breather vane") which will automatically increase the afforded flue opening 45 (when the main damper is not in its said "full open" position) in response to temperature changes within the flue.

Moreover, my invention aims to provide 50 simple, inexpensive, easily installed and not readily clogged plural damper means for this

purpose. Still further and also more detailed objects will appear from the following specification and from the accompanying drawings, in which

Fig. 1 is a central longitudinal section 55 through a portion of a flue pipe in which an embodiment of my invention is mounted, taken transversely of the pivot axis of the main damper and showing my plural damper means as positioned for affording the minimum effective flue passage for which they are 60 designed.

Fig. 2 is a reduced section taken transversely of the flue pipe along the line 2—2 of Fig. 1, when the temperature of the flue gases is 65 such that the thermostatic means have partly opened the supplemental gas passages formed in the main damper.

Fig. 3 is a fragmentary plan view, taken from the exterior of the flue pipe along the 70 line 3—3 of Fig. 1.

Fig. 4 is a fragmentary section, similar to the central portion of Fig. 1, but showing another form of thermostatic coil.

In the illustrated embodiment, the flue pipe 75 1 is provided with diametrically opposite perforations into which aligned bushings 2 and 3 extend radially of the pipe. Shaft portions 4 and 5 extend respectively through the bushings 2 and 3, and each of these shaft 80 portions is secured (as by rivets 6) to the main damper 7. This main damper (which may be a flat disk of sheet iron) is provided with a central and square perforation for receiving a correspondingly square-sectioned 85 end portion 8A of a pivoting shaft which extends at right angles to the face of the main damper 7 and which shaft end portion is riveted to that damper.

Pivoted on the shaft 8 is a secondary damper or "breather vane" 9 which desirably is spaced from the main damper 7 by a washer 10, to reduce friction. The secondary damper is fastened, as by a bracket 11, to the outer end of a spirally coiled thermostatic strip 12 90 made of a metal having a high coefficient of expansion, while the inner end of this coiled strip is secured, as by a rivet 13, to the pivoting shaft 8. This thermally responsive strip is desirably housed by a casing con- 95 100

sisting of the radially inner portion of the secondary damper and of a cup-shaped housing 14 which is secured at its mouth to the auxiliary damper. The cup bottom of this housing 14 desirably has a perforation 5 through which a diametrically reduced free end portion 8B of the pivoting shaft extends, so that the auxiliary damper and housing combination has two spaced bearings in which the pivoting shaft is journaled. Then I provide suitable means to prevent this secondary damper and housing combination from sliding along the shaft away from the main damper 7, such as a washer 15 engaging the 10 outer face of the cup bottom and a pin 16 extending through the pivoting shaft outside of (and adjacent to) this washer.

The two dampers are provided with perforations arranged so that the perforations 20 in the secondary damper will be moved into and out of alinement with the perforations in the main damper when the secondary damper is rotated about the pivoting shaft 8 which is fast upon the main damper. These 25 damper perforations are desirably sector-shaped, as shown in Fig. 2 for the perforations 17 in the main damper and the perforations 18 in the auxiliary damper; and the length of the coiled strip 12 is so selected that the coiling and uncoiling of this strip with 30 the excepted temperature changes in the flue pipe will move the secondary damper to and from positions in which the perforations in the latter damper are either completely in 35 alinement or completely out of alinement with those in the main damper.

Interlocked with one of the main damper shaft parts 4 is a resilient latching arm 17 by means of which this two-part shaft can 40 be rotated. This interlocking is here shown as made by outwardly turning the end of the latching arm 17 through which the said shaft part 4 extends, so that this turned up end 17A bears against a flat face of a collar 45 19 which is fastened to the shaft by a pin 20. This collar 19 is sufficiently spaced from the outer end of the adjacent journaling bushing 2, so that both the latching arm 17 and a latch plate 22 extend between the collar 50 and the said bushing. The latch plate also is perforated so that the said shaft part 4 extends through it, and is fastened to the flue pipe by a rivet 21.

This latch plate 22 desirably is substantially 55 quadrant-shaped and has at its arcuate edge an outwardly directed flange 23 provided with spaced recesses 24 into any one of which the resilient latching arm 17 can snap, after which the walls of entered recess 60 will prevent the latching arm from rotating, thereby holding the main damper against rotation in the flue. The latch plate also is desirably marked to indicate the "closed" and "open" positions between which the main 65 damper is movable, thereby indicating to

the user the minimum effective flue passage for which my composite damper has been set.

When the main damper is thus adjusted, the minimum flue passage is definitely fixed, 70 and if the flue is at the minimum temperature for which the thermostatic coil 12 is constructed, this coil holds the secondary damper (or breather vane) in a position in which the apertures 17 in that damper align 75 with the apertures 18 in the main damper, thus affording the maximum additional passage area past the main damper. However, when the temperature in the flue pipe rises, the thermostatic coil automatically rotates 80 the secondary damper about the pivoting shaft 8, so as to reduce the additional passage area until the temperature rises to the point where the perforations in the two dampers are entirely out of alinement, as 85 shown in Fig. 1.

Since this action of the spiral coil (or thermally responsive element) is independent of the setting of the main damper, the user can start with any suitable position of the latter, and can also change position of the main damper at any time that this may be desirable, so that my arrangement combines the advantages of the usual manually adjustable damper with those of a mere thermostatically controlled damper. 90 95

Besides being inexpensive in construction and easily installed, my combination damper can be used equally well in flue pipes of heaters employing different fuels, and as an 100 automatic substitute for the mere hand controlled dampers employed with so called economizers, hence I do not wish to be limited as to its use.

Moreover, while I have heretofore described my invention in an embodiment including numerous desirable details of construction and arrangement, I do not wish to be limited in these respects, as many changes might be made without departing either from the spirit of my invention or from the appended claims. 105 110

For example, instead of employing a thermostatic strip formed into a relatively flat coil, I may use an elongated spiral strip 115 25 surrounding a longer pivoting shaft 26 and shielded by a correspondingly longer housing 27, as shown in Fig. 4.

I claim as my invention:

1. The combination with a flue pipe, of a 120 rotatable shaft extending into the pipe radially of the pipe, a damper fast on the shaft and provided with a perforation, a control member movably mounted on the damper for varying the effective opening of the perforation; thermally responsive means for moving the control member; the said means including a spiral coil; and a housing for the said coil. 125
2. The combination with a substantially flat damper for a flue pipe, the damper having 130

perforations spaced from its center, of a control member adjacent to one face of the damper, pivoting means interposed between the damper and the control member for pivoting the control member coaxial with the damper, and thermally responsive means disposed radially inward of the said perforations and operatively interposed between the damper and the control member for moving the latter about the axis of the damper.

10 3. A damper for a flue pipe or the like comprising a circular main plate, a pivoting shaft fast upon and coaxial with the main plate, a secondary member having two portions journaled on longitudinally spaced portions of the shaft; a thermally responsive member coiled about the shaft and connected at its ends respectively to the shaft and to the secondary member; the plate and the secondary member being provided with counterpart sectoral perforations adapted to be alined when the plates are in one relative rotational position, the said perforations being spaced radially outward from the thermally responsive member.

25 4. For use in a flue pipe, the combination of a flat damper having perforations spaced from its center, a control member coaxial with and adjacent to the damper for controlling the passage of gas through the said perforations; a cup-shaped member having its mouth-end engaging the outer face of the control member and secured to the latter, a shaft coaxial with the damper and the control member and extending through the bottom of the cup-shaped member to afford a pivotal connection between the damper and the control member; and thermally responsive means housed by the cup-shaped member, the said means being operatively interposed between the damper and the control member for rotating the control member with respect to the damper in response to temperature changes.

30 45 Signed at Chicago, Illinois, February 13th, 1929.

ARTHUR C. McWILLIAMS.
